ROCKABLE FOOT AND LEG REST

Louis J. Brantl, 35 E. Garland Ave., Spokane, Wash.

Filed May 26, 1958, Ser. No. 737,707

3 Claims. (Cl. 155—169)

The present invention is a foot and leg rest having a rockable base and a tiltable support platform associated therewith in such a manner as to permit independent rocking and tilting movements of said base and platform in a coincident plane.

Applicant is aware that in the prior art there are ottomans which rock and some of which float and thus provide footrests which may be used in conjunction with a rocking chair, but each of these has some drawback or undesirable feature. In some instances, the footrest is merely an ottoman type which causes the weight of the limbs to be supported upon the heels of one using the footrest, which is very undesirable. Some of these ottomans have been provided with means which permit movement and therefore floating footrests which may be used with rocking chairs, but the support of the limbs on the heels soon becomes unbearable and the feet must be removed from the footrest.

There are others which provide foot and leg rests having a support member which extends along a portion of the leg, for instance, under the calf of the leg, while an angular portion supports the sole of the feet. These have been found to be more comfortable than the ottoman type, but impractical for use with a rocking chair, because in every instance of which the inventor is aware, the rocking members have been rigidly secured to the supporting platform, and therefore when the legs are moved forwardly by reason of a forward rocking movement in a chair, the rearward edge of the platform, pivoting over the rockers of the foot and leg rest, applies pressure to the back of the legs while attempting to lift the feet from the footrest portion, while rearward rocking movement in the rocking chair will cause the leg support portion to move downwardly from the legs and effect support of the legs and feet from the heels as aforementioned, while the footrest portion presses against the soles of the feet.

It has therefore been found that this prior art type of combined foot and leg rest is undesirable because it soon becomes tiring when one rocks in a rocking chair. Actually it results in immobilizing the rocking chair when this prior art foot and leg rest is in use.

Yet another type of foot and leg rest employed presently is one which has a rigidly supported base to which is pivotally secured a leg supporting platform having a foot rest angularly disposed relative thereto. This form, while effective as a foot and leg rest for a person who is completely immobilized, is ineffective for use with a rocking chair, and therefore in at least this situation is undesirable.

It therefore becomes one object of the present invention to provide a foot and leg rest which overcomes the aforementioned undesirable features and results in one which is admirably adapted for use with a rocking chair.

A further object of the present invention lies in the provision of a foot and leg rest which has a rocking base and a supporting platform pivotally mounted upon the base for tilting movements coincident to the plane of rocking movements of the base.

2

Another object of the invention lies in the provision of a foot and leg rest for use with a rocking chair which has a rocking base pivotally supporting a support platform for said tilting movements and provided with means for yieldably maintaining the support platform in a position intermediate its path of movement limits.

Yet another object of the present invention lies in the provision of a foot and leg rest for use with a rocking chair which is assembled with facility from a minimum number of parts and therefore one which is not liable to become inoperative because of long and continued use.

In the accompanying drawings forming a part of this specification, I have disclosed one physical embodiment of my present invention. It will be understood, however, that modifications and changes are contemplated and that I do not wish to be limited to that physical embodiment disclosed in the drawings, but that the drawings are exemplifying only to facilitate an understanding of the invention which I desire to cover broadly, limited only by the prior art as reflected in the appended claims.

In the accompanying drawings, wherein like numerals are employed to designate like parts:

Figure 1 is a diagrammatic side elevation of my improved foot and leg rest in a normal position as it may be used with a conventional four-legged chair;

Figure 2 is a similar view showing my improved foot and leg rest as employed with a rocking chair and showing the relative positions of the supporting platform and its base approaching their movement limits by alternate full and dotted line disclosures;

Figure 3 is an end elevation upon an enlarged scale and having portions broken away for convenience of illustration taken substantially on the plane indicated at line 3—3 of Figure 4; and

Figure 4 is a longitudinal cross section taken substantially on the plane indicated at line 4—4 of Figure 3.

Referring now more particularly to the drawings, my foot and leg rest for use with a rocking chair is indicated in its entirety by the numeral 10, and it will be seen 40 comprises a base 11 which is provided with means 12 for imparting manual rocking movements to the base 11. This means includes laterally spaced side plates 13 having curvilinear rocking faces 14 provided with recurvate extensions as at 15 to form stops for limits to the normal rocking movements of the base 11.

The side plates 13 are interconnected by crossbars 16, 16a, and 16b, which are rigidly fixed to the said side plates and form a unitary base 11. On the inner faces of the side plates 13 I provide stops 17 against which the side bars 18 of a supporting platform 19 strike to limit the tilting movement of the supporting platform 19 over the pivot formed by the crossbar 16b which is received in the upwardly extending recesses 20 formed in the side bars 18. Spacing washers 21 are provided to center 55 the supporting platform 19 on the base 11. A leg L is shown by broken lines as supported upon the platform 19.

At their outer ends the side bars 18 are provided with angularly disposed footrest supports 22. The side bars 18 are rigidly fixed in coincident relationship to each other 60 by means of cross members 24. To the upper or inner edges of the cooperating side bars 18 I secure a supporting plate 25 which is of a length and configuration substantially as shown in Figure 4. Over this plate I lay a cushion 26 which is preferably of sponge rubber, but other cushioning materials may also be employed, and thence a fabric or other covering as at 27 may be applied for the protection of the cushioning material and for providing esthetic values to the foot and leg rest.

A longitudinally extending support bar 28 is provided 70 with fastening means 29 at each end, each of which means, it will be seen, comprises an eye disposed laterally midway the width of the foot and leg rest. Tension springs

30 each have one end secured to said eyes 29 and the opposed ends of said springs are secured in eyes 31 which are fixed relative to the supporting platform 19 longitudinally spaced equidistant from the pivot axis at 16b. These springs and associated members constitute means for yieldably maintaining the supporting platform 19 substantially midway its limits of tilting movement with respect to the base 11.

To the footrest portion 32 of the foot and leg rest, I provide an electrically energized vibrator 33 so that one may selectively operate the vibrator to facilitate massaging the feet and therefore increase the comfort that may be derived by employing the foot and leg rest.

Having thus described one physical embodiment of my invention, I desire to secure by Letters Patent of the United States the following:

1. A foot and leg rest for use with a rocking chair comprising a base; laterally spaced rockers supporting said base for rocking movement; laterally extending tie bars rigidly associating said rockers with respect to each other; a foot and leg supporting platform pivotally mounted upon an upper one of said tie bars for tilting movements coincident to the plane of rocking movements of said base; tension springs each having its opposed ends secured to said supporting platform and to said base; and said springs being disposed spaced equidistant longitudinally of said foot and leg rest from said tie bar about which said leg support platform is pivoted, whereby to yieldably hold said supporting platform intermediate its tilting movement limits.

10 15 20 25 30

2. In a foot and leg rest for use with a rocking chair having a base including means for imparting manual rocking movement thereto, a foot and leg support platform comprising: a leg supporting portion and a foot supporting member at one end thereof and extending at an angle thereto; said leg supporting member being of a length and curvature to conform to the shape of a person's leg; means for pivotally associating said supporting platform for tilting movement coincident to the plane of rocking movements of said base; and resilient means for yieldably holding said platform intermediate its tilting movement limits with respect to said base.

3. A foot and leg rest for use with a rocking chair comprising a base having means for manually imparting rocking movements thereto; a foot and leg supporting platform pivotally mounted upon said base for tilting movements coincident to the plane of rocking movements of said base; and resilient means yieldably holding said platform with respect to said base intermediate its tilting movement limits.
